UNITED STATES PATENT OFFICE.

IVAN AUGUST MAURITZ LARSSON, OF STOCKHOLM, SWEDEN.

DESIGN FOR A PICTURE-HOOK OR SIMILAR ARTICLE.

42,970.

Specification for Design.

Patented Sept. 3, 1912.

Application filed February 8, 1911. Serial No. 607,438. Term of patent 14 years.

To all whom it may concern:

Be it known that I, IVAN AUGUST MAURITZ LARSSON, a subject of the King of Sweden, and a resident of 26 Hornsgatan, Stockholm, Sweden, have invented a new, original, and ornamental Design for Hooks or Hangers for Various Articles, Pictures, or Such Like, of which the following is a specification, reference being had to the accompanying drawing, forming a part thereof.

In the drawing, Figure 1 is a front elevation of the hook showing my design. Fig. 2 is a perspective view of the hook viewed from the side.

I claim:

The ornamental design for a picture hook or similar article as shown.

In witness whereof I have hereunto set my hand in presence of two witnesses.

IVAN AUGUST MAURITZ LARSSON.

Witnesses:

FRITZ E. HALLIN,
MARIA LUNDBLAD.
